(57) **CLAIM**

The ornamental design for a smart jumper cable, as shown and described.

DESCRIPTION

FIG. 1 is a top isometric view of a smart jumper cable, showing my new design;

FIG. 2 is a top plan view of thereof;

FIG. 3 is a bottom plan view of thereof;

FIG. 4 is a front elevation view thereof;

FIG. 5 is a back elevation view thereof;

FIG. 6 is a right side elevation view thereof; and,

FIG. 7 is a left side elevation view thereof.

The broken lines represent portions of the smart jumper cable and form no part of the claimed design.
